Primary Examiner — Elizabeth J Oswecki*(74) Attorney, Agent, or Firm* — Gokalp Bayramoglu**CLAIM**

The ornamental design for a pistol safe, as shown and described.

DESCRIPTION

FIG. 1 is a top view of a pistol safe showing my new design; FIG. 2 is a bottom view thereof; FIG. 3 is a front view thereof; FIG. 4 is a back view thereof; FIG. 5 is a right side view thereof; FIG. 6 is a left side view thereof; FIG. 7 is a top perspective view thereof; FIG. 8 is a partial enlarged view taken on encircled portion labeled FIG. 8 in FIG. 7; FIG. 9 is a front perspective view thereof; FIG. 10 is a back perspective view thereof; and, FIG. 11 is a perspective view thereof, shown in a used condition with the hexagon door open and a key shown in broken lines. The broken lines depict portion of the pistol safe form no part of the claimed design.
